FIG. 1.

FIG. 2.

FIG. 3.

UNITED STATES PATENT OFFICE.

THOMAS ENGLEMAN ACKLEN, OF MEMPHIS, TENNESSEE.

RESUSCITATOR.

1,175,671.

Specification of Letters Patent. Patented Mar. 14, 1916.

Application filed June 21, 1915. Serial No. 35,312.

To all whom it may concern:

Be it known that I, THOMAS E. ACKLEN, a citizen of the United States, and a resident of Memphis, in the county of Shelby 5 and State of Tennessee, have invented an Improvement in Resuscitators, of which the following is a specification.

My invention is an improvement in resuscitators, and the invention has for its 10 object to provide a device of the character specified, suitable for use with persons suffering from suspended respiration, and wherein mechanism is provided adapted to be secured in place on the upper portion of 15 the abdomen and adjacent portion of the stomach, for moving the wall of the abdomen outward and inward, in a manner simulating respiration, in order to restore the function of breathing.

20 In the drawings:—Figure 1 is a side view showing the device in use, Fig. 2 is an enlarged section on the line 2—2 of Fig. 1, Fig. 3 is a section on the line 3—3 of Fig. 2.

The present embodiment of the invention 25 comprises a base 1, formed from a sheet of rubber or like elastic material, and of suitable width and length, and a portion of the sheet at the center thereof is partially separated from the sheet to form a 30 valve 2. This valve is of rectangular form, being separated from the sheet on three sides, as clearly shown in Figs. 2 and 3, the valve being connected to the sheet at the third side. A substantially rectangular 35 frame 3 is arranged on the outer face of the sheet at the opening 4 formed by the valve 2, and this frame, as shown, is of considerable length, the walls thereof being right rectangular in cross section. The bottom 40 and the inner face of the frame are, as shown in Figs. 2 and 3, of equal width, and the outer face 5 is concave. The frame and the valve are of such relative dimensions, that the valve may be moved freely 45 within the frame, yet the edges of the opening 4 will be at the inner face of the frame. In other words the opening 4 is of the same area as the cross section of the frame 3. One end of a tapering frusto-conical bellows 6 is connected with the end of the frame 3 remote from the sheet. The opposite end of the bellows is connected to a plate 7, the said plate being of a size to fit within the bellows 6, and a sheet or plate 55 8 of rubber is arranged on the outer face of the plate 7.

A handle 9 in the form of a bail is secured to the sheets 7 and 8, by means of rivets 10 or the like, and valve casings 11 are arranged at each side of the handle, in 60 openings in the sheets 7 and 8. Each valve casing is in the form of a cap, having its closed end 12 outward, and each of the closed ends is provided with a central port or passage 13. Each valve casing is provided with a transverse diaphragm 14 intermediate its ends, and each diaphragm has a central tapering seat, with which operates a ball valve 15. The valve moves in a compartment formed between the 70 closed outer end 12 and the diaphragm 14, and the said valves permit the air to move outward freely from the casing formed by the bellows and the frame, but prevent the entrance of air. Each valve casing is 75 flanged outwardly at its ends as indicated at 16, the said flanges engaging remote faces of the sheets 7 and 8, to hold the casings from movement longitudinally. The small end of the bellows is extended over 80 the side edges of the sheets and beyond the outer face of the sheet 8, and the material of the bellows is then lapped upon the outer face of the sheet as indicated at 17. In practice, the sheet 8 is vulcanized in place 85 and is connected to the bellows by vulcanizing or in any suitable manner. The frame 3 is also of vulcanized rubber, and strips 18 of leather or the like are connected at one end to one side edge of the sheet 1. It will 90 be noticed that the said sheet is of greater area than the frame, and extends beyond the frame at all sides thereof, and preferably the sheet is provided near each side edge with a reinforcing rib 19 integral with 95 the sheet. These ribs extend parallel with the side edges, but in spaced relation, and it will be noticed from an inspection of Figs. 2 that the strips 18 are secured to the sheet outside of the adjacent rib. Each strip is 100 provided at its free end with a longitudinally extending series of openings 20, and these openings are designed to be engaged by hooks 21 secured to the opposite side edge of the sheet. Three strips are shown, but 105 it is obvious that as many strips may be used as may be thought necessary or advisable.

In use, the device is arranged as shown in Fig. 1, being placed on the body of the patient over the pit of the stomach, and extending down over the abdomen. The patient is laid upon his back as shown, and

preferably the shoulders are elevated slightly so as to hold the neck straight. The strips are secured in place, to hold the device snugly to the patient, and after the device is secured, as above mentioned, the bellows are expanded by pulling upward on the handle 9. When the handle is moved upward to expand the bellows it will be obvious that the abdomen wall will be moved with the flap valve 2. A downward pressure is then made on the bellows by means of the handle 9, and as the bellows contracts a portion of the air in the casing is driven out past the valve 15. This movement is continued at regular intervals, until respiration is restored. Whenever the bellows is expanded, the abdomen wall being pulled outward will cause the diaphragm to move downwardly, thus expanding the lungs, and air will rush into the lungs through the air passages. When the bellows is contracted the flap valve 2 is forced downwardly making pressure on the abdomen wall, and forcing up the diaphragm, thus driving out the air from the lungs. The movement may be made to closely simulate natural respiration, and it will be evident that the device may

be used for many purposes, as for instance, to restore respiration after partial asphyxiation from drowning, gas poisoning, electric shock, or the like.

The device is light in form, easily portable, and there is nothing to get out of order easily. In addition the device is inexpensive, and the upkeep will be negligible.

I claim:

A device of the character specified, comprising a sheet of flexible elastic material having means for securing the sheet to the body of the person operated upon, said sheet having a central opening, a frame encircling the opening and secured to the outer face of the sheet, a bellows having one end connected to the frame, a plate closing the outer end of the bellows and having a handle, said plate having openings and valve casings in the openings, and a check valve in each casing, each valve casing being tubular and having its outer end closed and provided with a central bore, and having a transverse diaphragm provided with a bore, and a ball valve co-operating with the bore.

THOMAS ENGLEMAN ACKLEN.
